CLAIM

I claim the ornamental design for an extension pole male repair tool, as shown.

DESCRIPTION

FIG. 1 of the drawings is a perspective view showing the front, right side, and top of an extension pole male repair tool embodying the design of my invention, with a typical extension pole environment depicted by phantom lines that are for example only and form no part of the claimed invention;

FIG. 2 is a front view;

FIG. 3 is a left side view;

FIG. 4 is a bottom view; and,

FIG. 5 is a back view.
